UNITED STATES PATENT OFFICE.

GEORGE A. KELSALL, OF NEW YORK, N. Y., ASSIGNOR TO WESTERN ELECTRIC COMPANY, INCORPORATED, OF NEW YORK, N. Y., A CORPORATION OF NEW YORK.

LOADING UNIT FOR TELEPHONE SYSTEMS.

1,238,153.

Specification of Letters Patent. Patented Aug. 28, 1917.

Application filed December 29, 1916. Serial No. 139,531.

To all whom it may concern:

Be it known that I, GEORGE A. KELSALL, a citizen of the United States, residing at New York, in the county of New York and

5 State of New York, have invented certain new and useful Improvements in Loading Units for Telephone Systems, of which the following is a full, clear, concise, and exact description.

10 This invention relates to loading units for telephone systems, and particularly to a loading unit adapted for the simultaneous loading of two physical circuits and their derived or phantom circuits.

15 In an arrangement described and claimed in an application of J. B. Speed, Serial No. 88,072, filed March 31, 1916, and assigned to the same assignee as the present applica-

20 tion, the simultaneous loading of two physical circuits and their derived phantom circuit is provided for by means of a loading unit characterized by two toroidal core members intersecting on a common diameter. In said loading unit, the two line windings in-

25 dividual to one of the physical circuits are located on opposite halves of one toroid, and the line windings individual to the other physical circuit are located on opposite halves of the other toroid. Each physical

30 circuit is thus loaded independently of, and without interference with, the other physical circuit. Furthermore, when phantom circuit currents flow through the windings of this loading unit, the distribution of flux

35 is such as to load the phantom circuit in addition to the physical circuits.

It is an inherent characteristic of a loading unit of the kind just described that the mutual inductances between all line wind-

40 ings are very nearly equal, as a result of which the phantom circuit inductance is only fifty per cent. of the physical circuit inductance. This is due to the fact that for

45 phantom circuit operation the two line windings of each toroid are connected in parallel and the two parallel circuits thus formed are connected in series. The resultant inductance therefore is equal to that operative in a single line winding; that is, the self-

50 inductance of a line winding plus its mutual inductance to an adjacent winding. The mutual effects of the remaining windings being in opposite directions cancel each other. The physical circuit inductance on

55 the other hand is that due to two line windings in series, which in effect is the sum of

the two self-inductances plus twice their mutual inductance. It has been found in practice, however, taking into consideration the mutual capacity of the phantom circuit 60 as compared with the mutual capacity of the physical circuit, that, in order to load a phantom circuit to the best advantage, its inductance should be approximately sixty per cent. of the physical circuit inductance. 65

The present invention may be considered an improvement upon the invention covered by the application of J. B. Speed hereinbefore mentioned, in that it modifies the relation of the physical circuit inductance to the 70 phantom circuit inductance so that the latter is approximately sixty per cent. of the former, thereby satisfying the requirement before mentioned.

The invention is characterized by the provision in the magnetic structure of gaps of high reluctance which are so located that they increase the reluctance of the paths traversed by the physical circuit flux, but do not substantially increase the reluctance 75 of the paths traversed by the phantom circuit flux; thus destroying the balance between the mutual inductances previously referred to so as to add the phantom circuit inductance and at the same time subtract 80 from the physical circuit inductance.

The invention will be understood from the following description taken in connection with the accompanying drawing, in which Figure 1 is a perspective view of a 90 loading unit embodying one form of the invention; and Figs. 2 and 3 are perspective views of core members for loading units embodying other forms of the invention.

The core members shown in Figs. 1, 2 95 and 3 and hereafter described may be of any suitable magnetic material. For example, they may conveniently be formed of finely divided iron, the individual particles of which are insulated from one another, 100 the core material being molded by high pressure, in the manner described and claimed in an application for patent of J. B. Speed, Serial No. 89,409, filed April 6, 1916, and assigned to the same assignee as 105 the present application. Such core material may be readily worked to the desired shapes by molding and cutting.

Referring to Figs. 1, 2 and 3, the core structure of each loading unit is shown as 110 comprising two toroidal core members 1 and 2 arranged to intersect at right angles

on a common diameter. Ways in which the core members 1 and 2 engage will be clear from the drawing. In Fig. 1, windings 3 and 4 are shown located upon opposite 5 halves of core member 1, and are intended for inclusion in the line conductors of one physical circuit; and windings 5 and 6 are located upon the opposite halves of core member 2, and are adapted for inclusion in 10 the line conductors of the other physical circuit, as described in the aforesaid application of J. B. Speed, Serial No. 88,072. The whole structure may be held together in any suitable manner, as by a belt of tape 15 7 encircling the structure and held taut by cords 8, substantially as shown in Fig. 1. The core structures shown in Figs. 2 and 3 may be similarly provided with windings, and may be held together in the same manner.

Figs. 1, 2 and 3 show differently shaped gaps of high reluctance which may be located in the core members 1 and 2 at their points of juncture. All of said gaps extend radially 25 through the points of juncture of the core members 1 and 2, but do not completely intersect said core members. As shown in Fig. 1, the gaps are in the form of slots 11 and 12 located, respectively, in the core 30 members 1 and 2 at their points of juncture, and in planes at substantially right angles to one another. As shown in Fig. 2, the gaps are in the form of round holes 13 and 14 through the core members 1 and 2 at 35 their points of juncture. And in the core structure shown in Fig. 3, the gaps are in the form of crossed slots in the core members 1 and 2 at their points of juncture. Said gaps may be either left unfilled or may 40 be filled with some non-magnetic material, such as fiber, for purpose of mechanical strength, as shown at 15 in Fig. 3.

As explained in the aforesaid application of J. B. Speed, Serial No. 88,072, the physical 45 circuit flux due to the windings 3 and 4, threads and is confined to the core member 1; and the physical circuit flux due to the windings 5 and 6, threads and is confined to the core member 2; and the phantom 50 circuit flux due to said windings all passes from one point of juncture through the two halves of core member 1 to the other juncture, and back through the two halves of the other core member 2 to the first-mentioned 55 juncture. In Figs. 1, 2 and 3, the paths of the physical circuit flux are indicated by arrows made with full lines; and the paths of the phantom circuit flux are indicated by arrows made with dash lines.

60 It will be obvious from the foregoing description and from the drawing, that the gaps of high reluctance of the various forms shown and described, will increase the re-

luctance in paths traversed by the physical circuit flux without substantially increasing 65 the reluctance of the paths traversed by the phantom circuit flux. By suitably proportioning said gaps, it is possible to make the reluctance of the path traversed by the phantom circuit flux such that the inductance 70 operative in the phantom circuit is substantially sixty per cent. of that operative in each of the physical circuits; which is the relation desired, as hereinbefore explained.

It will be understood that, while in the 75 drawing core structures are shown in which the core members are substantially square in cross-section, they may, if desired, have other cross-sectional forms. The term "toroid" used herein is intended to refer to 80 a ring of any desired cross section. It will also be understood that, instead of rings, rectangular or other forms of frames and closed figures might be employed, and that, for want of some broader expression, the 85 term "toroid" is used to denote all such structures.

What is claimed is:

1. A loading unit having a plurality of core members each in the form of a closed 90 figure, said members intersecting at a plurality of points and being provided with gaps of high reluctance at the intersections.

2. In a loading unit for physical and phantom circuits, intersecting core members 95 having gaps at the intersections, said gaps offering different reluctances to physical and phantom circuit flux.

3. A loading unit having two toroidal core members intersecting on a common diameter and having gaps of high reluctance 100 therein at the points of juncture of said members.

4. A loading unit having two toroidal core members intersecting on a common diameter and having gaps of high reluctance 105 therein extending radially through the points of juncture of said members.

5. A loading unit having two toroidal core members intersecting on a common diameter and having gaps of high reluctance 110 therein in the form of openings extending radially through but not completely intersecting said members at their points of juncture.

6. A loading unit having two toroidal core members intersecting on a common diameter and having gaps of high reluctance 115 therein in the form of slots passing radially through said members at their points of juncture, said slots being in planes at substantially right angles to one another.

In witness whereof, I hereunto subscribe my name this 28th day of December, A. D. 1916.

GEORGE A. KELSALL.
